UNITED STATES PATENT OFFICE

ARCANGELO TOSCANO, OF NEW YORK, N. Y.

NAUTICAL CYLINDER OR TUBE

Application filed June 13, 1929. Serial No. 370,497.

This invention relates to the increasing of the speed of any aerial or maritime ships by means of a cylinder or tube which I intend to call "Toscano cylinder."

This object is obtained by shutting up and sending back compact into a cylinder or tube the air or water displaced by any propeller, which otherwise would escape sideways and through the application of this invention is utilized as a pushing energy. The air or water so shut up and canalized into a cylinder or tube, not only makes the propeller work in an undisturbed area, but by way of escaping compact from the rear of said cylinder or tube, makes such a stream that it pushes the ship ahead and causes the said propeller to have two instead of one moving powers, to wit: a paddling on its anterior side and a pushing power on its posterior side, thereby increasing the normal speed of any ship.

The shape and length of the cylinder or tube may be varied according to the results wished to be obtained, but the internal diameter of the cylinder or tube should always remain equal in size to the diameter of the propeller with its anterior extremities slightly conical for a short tract, in order to avoid that the cylinder or tube in its possible vibration may be struck by the propeller.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:—

Fig. 1 is a vertical longitudinal sectional view of a cylinder for use according to this invention.

Fig. 2 is a side elevational view of an airship provided with cylinders according to this invention.

Fig. 3 is a fragmentary sectional view taken on the line 3—3 of Fig. 2.

Fig. 4 is a fragmentary sectional view taken on the line 4—4 of Fig. 2.

Fig. 5 is a front elevational view of an aeroplane with the invention applied.

Fig. 6 is a plan view of Fig. 5.

Fig. 7 is a side elevational view of a boat with the invention applied.

Fig. 8 is a side elevational view of a portion of a submarine with the invention applied.

Fig. 9 is a fragmentary end elevational view of Fig. 7.

Fig. 10 is a vertical sectional view of a cylinder constructed according to this invention but of modified form.

Fig. 11 is a similar view of a further modification.

Fig. 12 is a fragmentary view similar to Fig. 11, showing a further modification.

The reference numeral 15 indicates generally a tubular member having its front end slightly conical indicated by numeral 16 for providing clearance for a propeller of substantially the same diameter as the inside of said member. The propeller is indicated by dotted lines 17, and in application the longitudinal axis 18 of the tubular member should coincide with the longitudinal axis of the propeller. The vertical axis of the rear end of the tubular member should coincide with the vertical axis of the propeller and the propeller should be so positioned that half lays within the tubular member indicated by reference numeral 19 and its other half outside as indicated by numeral 20.

In Figs. 2, 3 and 4, a lighter than air flying machine 21 has been illustrated provided with a central front motor 22 connected with a propeller 23. This flying machine also has a pair of spaced motors 24 connected with propellers 25. These motors are secured upon the flying machine by struts 26. The tubular member 15 is supported to the rear of the propeller by struts 27.

In Figs. 5 and 6, a heavier than air flying machine 28 has been illustrated provided with dual motors 29. These motors connect with propellers 30 and a pair of tubular members 15 are supported to the rear of the propellers by struts 31.

In Figs. 7 and 9, a ship 32 has been illustrated provided with a propeller 33. A tubu-

lar member 15 is supported to the rear of the propeller by struts 34. In Fig. 8 a submarine 35 has been indicated provided with a propeller 33 and a tubular member 15 is supported to the rear of the propeller by struts 34.

Upon operation of the propeller, a stream of air is sent thru the tubular member and the tubular member prevents the stream from moving laterally, that is, providing maximum forward propelling, in that the stream may move rearwards only. It has been found that this materially increases the speed at which the vessel may travel.

In Fig. 10, a modified form of cylindrical member 15 has been illustrated provided with a conical end 16. A propeller 17' is shown engaged in the conical end of the tubular member so that half of the propeller extends within the member indicated by numeral 19' and the other half is disposed outside of the member indicated by 20'. The opposite end of the tubular member is provided with vertical rudders 36 and horizontal rudders 37. The vertical rudders 36 are positioned internally in the tubular member while the horizontal rudders 37 are positioned outside, that is externally. Customary connections may be used to operate these rudders. The purpose of these rudders is to give more agility to the ship because the stream of air or water canalized into the cylinder or tube pushes against the said rudders. In aerial navigation the cylinder or tube is provided with wings in the construction of aeroplanes irrespective of the location of the fuselage and in the construction of dirigibles and maritime ships the tubes or cylinders are attached to the dirigible or ship at the rear of the propeller as shown in Figs. 2, 7 and 8.

The interior and exterior of the nautical cylinder or tube must be free from any projections with the exception of the strictly necessary ones in order not to cause any resistance to the air or water in its course thus giving a strong and solid stability of direction to the ship.

In the modified form illustrated in Fig. 11, the rudders 36 and 37 are shown provided with spindles 38 extending thru slots 39 in the tubular member. The ends of the spindles are rotatively engaged in bearings 40. These bearings are threadedly engaged by screws 41 arranged at right angles to the spindles 38 and rotatively mounted in lugs 42 projecting from the sides of the cylinder 15. The screws may be manually rotated for moving the rudders forwards or rearwards so as to be differently positioned relative to the end of the tubular member 15. Such adjustments are very beneficial for different types of machines.

In Fig. 12 the rudders 36 and 37 are arranged externally on the tubular member 15 and by means of screws 41' it is possible

to change their relative position with respect to the said tubular member.

Generally speaking, the return from motor propellers is from 50 to 70%. The medium or average return is 65% of the power transmitted to the propeller. The return of a propeller provided with a tubular member according to this invention is substantially 100% of the power transmitted to it. Quite obviously this is of extreme advantage and the following example is given for purpose of illustration. In a cruiser in which 20,000 H. P. engines are used, the return from those engines is 80%, that means a power return of 16,000 H. P. The medium or average propeller return is 65% which gives the utilized power as 10,400 H. P. Should this cruiser use a tubular member according to this invention, the propeller return would be substantially 100% so that the utilized power would be 16,000 H. P. Actual speed without the tubular member may be assumed 20 knots an hour and it is known that speeds are in ratio with the cubic roots of the powers and so the powers are between them as the cubic roots of the speeds. Further, it is pointed out that

$$\frac{V^3}{20^3} = \frac{16,000}{10,400}$$

$$V^3 = 20^3 \times \frac{16,000}{10,400}$$

Speed equals 23.2 knots approximately. Further 16% more of the first speed with less consumption and load of fuel which gives a still higher percentage of speed.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. In combination with a motor driven propeller, a tubular member in line with the discharge of the propeller and arranged to canalize the discharge and prevent lateral escapement, and horizontal and vertical rudders arranged in the discharge of the tubular member, said rudders being arranged for adjustment relative to the discharge end of the tubular member, spindles projecting from said rudders and extending thru slots in said tubular member, bearings supporting the ends of the spindles, and screws at right angles to the spindles adjustably supporting the bearings and rotatively mounted on the tubular member accomplish the adjustment of the rudders.

2. In combination with a motor driven propeller, a tubular member in line with the

discharge of the propeller and arranged to canalize the discharge and prevent lateral escapement, and horizontal and vertical rudders arranged in the discharge of the tubular member, said rudders being arranged for adjustment relative to the discharge end of the tubular member, bearings pivotally supporting the rudders, and screws adjustably supporting the bearings and rotatively mounted on the tubular member accomplish the adjustment of the rudders.

In testimony whereof I have affixed my signature.

ARCANGELO TOSCANO.
